Attorney.

UNITED STATES PATENT OFFICE.

CHARLES DAVID BONSALL, OF NEW KENSINGTON, PENNSYLVANIA, ASSIGNOR TO UNION METAL PRODUCTS COMPANY, OF CHICAGO, ILLINOIS, A CORPORATION OF DELAWARE.

DEVICE FOR OPERATING CAR COUPLERS.

Original application filed October 24, 1924, Serial No. 745,635. Divided and this application filed April 13, 1925. Serial No. 22,667.

This particular invention relates to what is generally known in the art as a rotating type of uncoupling device for car couplers and comprises an operating rod revolvably 5 mounted on the car with brackets or in any other convenient manner, which rod is usually bent downwardly at the outer end to form a handle, and is bent outwardly at its inner end to form a crank, projecting over 10 the coupler, which crank is provided with a horizontally positioned eye with its axis perpendicular to the longitudinal center of the car. The standard vertical plane coupler has a knuckle pivoted to the coupler head 15 and provided with a tail behind which the lock is placed. The lock lifter protrudes through and above the coupler head and is provided with a horizontally positioned eye. This lock lifter eye is $1\frac{1}{16}$ " in diameter and 20 its axis is perpendicular to the longitudinal center of the car. This size and position has been determined by the American Railroad Association and is standard for the majority of couplers now in service.

25 My invention resides in the connection between the eye on the crank of the operating rod and the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between 35 the coupler and the operating rod must permit such movements without the component parts becoming disengaged from each other or from either the coupler or the operating rod. It is frequently necessary to uncouple 40 cars when they are coupled together and in contact so that it is impossible to throw the knuckle of either coupler. To meet this condition couplers are designed to assume a "lock set position" wherein the lock lifter 45 can be raised from behind the tail of the knuckle and retained in such a position by means within the head of the coupler independent of the operating rod. This allows the operating rod to fall close to the lock 50 lifter. To accommodate such a movement the connection between the operating rod crank and the coupler must fore-shorten,

which is accomplished by making it of several parts which collapse by means of a hinge joint or a sliding connection to each other, or, as in my design, the component parts are pivotally and slidably connected. The operating rod, as above described, is old and in use on hundreds of thousands of cars now in existence. Such rods had a 60 short chain connecting the crank arm to the lock lifter of the coupler which chains proved unsatisfactory and were responsible for a little more than half of the defects for uncoupling mechanisms reported by the 65 Interstate Commerce Commission. These chains were defective because they were broken, missing, kinked and either too long or too short.

One of the objects of this invention is to 70 provide a connection between the rod and the coupler which will eliminate the defects of the old chain and meet all service conditions required.

These short chains were broken by falling 75 behind the coupler horn and being smashed between the coupler horn and the striking casting by impact of the cars in coupling. The device is designed so that the component parts cannot become disconnected from 80 each other or from the operating rod or the coupler. The connection between the component parts and also their connections to the operating rod and the coupler are such that the device cannot become "kinked." 85 Formerly when a brakeman wanted a small chain to repair one of the old connections he simply guessed as to the amount of chain required and applied it to the car, which accounts for the number of "too long" and 90 "too short" chains reported by the commission. This is not possible with my device.

Another object is to provide a connection which may be hooked into the eye of the coupler lock lifter with the hooked member 95 connected to the crank of the operating rod by another member which permits it to adapt itself to the various service movements of the coupler but prevents it from becoming disengaged from the lock lifter in 100 service.

Another object of the invention is to provide a device wherein the component parts are identical and duplicates, therefore, inter-

changeable. Duplication, of course, also simplifies manufacture, handling, accounting, etc.

Another object is to obtain a device wherein the component parts are duplicates so that they cannot be wrongfully applied to the car or to each other.

In the drawings:

Fig. 1 is a perspective view of a portion 10 of a car with my invention applied thereon.

Fig. 2 is an elevation of the connector.

Fig. 3 is a side elevation of Fig. 2.

Fig. 4 is a pair of members per Figs. 2 and 3 in open position.

Fig. 5 shows the connector in extended 15 position.

Fig. 6 is the connecting pin.

Fig. 7 is an end view of Fig. 6.

In a railway car the operating rod 1 is 20 mounted on the end sill 2 by brackets 3. The usual operating rod has a handle 4 and a crank arm 5 which arm has a horizontally disposed eye 6. The lock lifter 7 of the coupler 8 also has a horizontally disposed eye 9 and my invention resides in a connector 25 for these two mentioned eyes.

The device comprises two pairs of complementary hooked and preferably duplicate members. The members of each pair are shaped to be positioned opposite each other to form a closed eye.

The two upper members 40—41 are hooked into the eye 6 of the crank arm 5, as shown in Fig. 4, and moved opposite each other to 35 form a closed eye. The two lower members are similarly hooked into the eye 9 of the lock lifter 7 and moved opposite each other to form a closed eye.

The shank 42 of the pin 43 which engages the slots 45 in all four members is 40 rectangular, preferably elongated, so as to prevent any pivotal action of the members thereby retaining all of them in the position forming a closed eye. The pin 42 with its 45 nut 44 secures the component parts of the connector together and holds the pin in place. In other words, the single pin retains the component parts together and also holds the device in operative position on the 50 car. Figs. 2 and 5 show how the connector may alter its length to accommodate service conditions.

All four component parts are preferably identical.

55 This is a division of my co-pending application Serial No. 745,635, filed October 24, 1924.

I claim:

1. A connector for a railway car coupler 60 and its operating rod, comprising a plurality of members, each having a hook at one end and a hole at its opposite end, said hooks positioned complementarily to form closed eyes at the opposite ends of the connector, a pin non-rotatively engaging all of said 65

holes so as to retain said members in the position forming the said closed eyes, and means to hold said pin in place.

2. A connector for a railway car coupler 70 and its operating rod, comprising a plurality of members, each having a hook at one end and an elongated hole at its opposite end, said hooks positioned complementarily to form closed eyes at the opposite ends of the connector, a pin non-rotatively engaging 75 all of said holes so as to retain said members in the position forming the said closed eyes, and means to hold said pin in place.

3. A connector for a railway car coupler 80 and its operating rod, comprising a plurality of duplicate members, each having a hook at one end and an elongated hole at 85 its opposite end, said hooks positioned complementarily to form closed eyes at the opposite ends of the connector, a pin non-rotatively engaging all of said holes so as to retain said members in the position forming 90 a closed eye, and means to hold said pin in place.

4. A connector for a railway car coupler 90 and its operating rod, comprising four members arranged to form two pairs of complementary members, each pair of complementary members positioned opposite each other to form a closed eye, and a single means nonpivotally securing said pairs of complementary members together and connecting the members of each pair together.

5. A connector for a railway car coupler 100 and its operating rod, comprising four identical members arranged to form two pairs of complementary members, each pair of complementary members positioned opposite each other to form a closed eye, and a single means non-pivotally securing 105 said pairs of complementary members together.

6. A connector for a railway car coupler 110 and its operating rod, comprising four members arranged to form two pairs of complementary members, each pair of complementary members positioned opposite each other to form a closed eye, and a single means non-pivotally but slidably securing 115 said pairs of complementary members together and connecting the members of each pair together.

7. A connector for a railway car coupler 120 and its operating rod, comprising four identical members arranged to form two pairs of complementary members, each pair of complementary members positioned opposite each other to form a closed eye, and a single means non-pivotally but slidably securing 125 said pairs of complementary members together.

8. A connector for a railway car coupler 130 and its operating rod, comprising four members arranged to form two pairs of complementary members, each pair of complementary members positioned opposite each

other to form a closed eye, and a single means non-pivotsly securing said pairs of complementary members together, said means also retaining said members in the 5 position forming said closed eyes.

9. A connector for a railway car coupler and its operating rod, comprising four identical members arranged to form two pairs of complementary members, each pair 10 of complementary members positioned opposite each other to form a closed eye, and a single means non-pivotsly securing said pairs of complementary members together, said means also retaining said members in 15 the position forming said closed eyes.

10. A connector for a railway car coupler and its operating rod, comprising four members arranged to form two pairs of complementary members, each pair of complementary members positioned opposite each other to form a closed eye, and a single means non-pivotsly but slidably securing said pairs of complementary members together, said means also retaining said members in 20 the position forming said closed eyes.

11. A connector for a railway car coupler

and its operating rod, comprising four identical members arranged to form two pairs of complementary members, each pair 30 of complementary members positioned opposite each other to form a closed eye, and a single means non-pivotsly but slidably securing said pairs of complementary members together, said means also retaining said 35 members in the position forming said closed eyes.

12. In a railway car, the combination of an operating rod mounted upon the car having a horizontally disposed eye, a coupler with a lock lifter having a horizontally disposed eye, and a connector therefor comprising a plurality of members, each having a hook at one end and a hole at its opposite end, said hooks positioned complementarily 40 to form closed eyes at the opposite ends of the connector, a pin non-rotatively engaging all of said holes so as to retain said members in the position forming the said closed eyes, said closed eyes forming engagements 45 to the lock lifter eye and operating rod eye, respectively. 50

CHARLES DAVID BONSALL.
